UNITED STATES PATENT OFFICE.

FREDERICK LEININGER, OF NEW YORK, N. Y., ASSIGNOR TO CHARLES DE B. SHEPARD, OF SAME PLACE.

STEP FOR SPINDLES.

SPECIFICATION forming part of Letters Patent No. 377,902, dated February 14, 1888.

Application filed June 4, 1887. Serial No. 240,294. (No model.)

To all whom it may concern:

Be it known that I, FREDERICK LEININGER, a citizen of the United States, residing at New York, in the county of New York, State of New York, have invented certain new and useful Improvements in Steps for Spindles, of which the following is a specification, reference being had therein to the accompanying drawings.

The object of this invention is to provide a step for the reception and support of spindles for centrifugal and other machines adapted to run at an exceedingly high speed, whereby the friction attending the running of the same is reduced to a minimum, means for lubricating the same uniformly and at all times, and to provide an adjustment for the spindle whereby the same may be raised and lowered to desired positions.

Other objects and advantages of the invention will hereinafter appear, and the novel features will be particularly pointed out in the claims.

Referring to the drawings, Figure 1 is a central vertical section of the lower end of a spindle provided with a step constructed in accordance with my invention; and Fig. 2 is a similar view, the spindle being mounted for rotation in the base of a centrifugal machine and provided with lubricating devices constructed in accordance with my invention.

Similar letters of reference indicate like parts in both figures.

A represents the base of a centrifugal machine, which in this instance is of ordinary construction and formed with the openings A' A² and the bridge or transverse partition A³, provided at its center with the flanged bushing A⁴. Fixedly secured within the bushing A⁴ is the step-case B, centrally bored to receive an interposed lining or sleeve, B^x, and screw-threaded at its bottom interiorly, as at B', to receive an exteriorly-screw-threaded and interiorly-bored spindle-step, C, formed with the seat C' and the adjusting-pins C². Mounted upon the screw-threaded exterior of said spindle-step is a set-wheel, C³, for retaining the spindle-step at the desired elevation after being adjusted by the pins C². Coupled to the bottom of the spindle-step by means of a screw-threaded nut, D, is a screw-threaded tube, D',

communicating with the bore in the spindle-step, and to the bottom of the tube D' is connected the oil-duct E', which extends out of the base through the opening A' and upwardly 55 to a height above the plane of the spindle-seat C', where it is provided with an oil receiver or cup, E. By this arrangement of the oil-duct and the parts to be oiled it is evident that oil may be conveniently poured into the cup and 60 will flow down through the duct and up through the tube D' to the spindle-seat C'.

It has been found by experience that, no matter what precautions were taken to prevent it, there are occasions when, by reason of the very 65 high speed of rotation at which the spindle is run, said spindle will become heated and stick in its seat. This causes a sudden stoppage of the spindle, and, besides causing great delay and trouble before repairment can be accomplished, the sudden stop causes a breakage of the different parts making up the machine. By the peculiar and novel manner of mounting the spindle in the spindle-step I overcome 70 the liability of overheated bearings, and, even 75 should this occur or the parts break, the stoppage of the spindle would be gradual and attended with no injury.

Referring more particularly to Fig. 1 of the drawings, which is an enlarged view showing 80 the manner of seating the spindle within its bearing, F represents the spindle, the upper portion of which is broken off. In the bottom of the spindle F is formed a conical socket, F', which is adapted to receive and snugly fit the 85 conical end G' of a lower spindle, G, provided with a central indenture or recess, G², in its bottom for the admission of the lubricant. The lower spindle, G, is of a size adapted to fit loosely within the spindle-seat C'; and interposed between said spindle and said seat are a series of cylindrical washers, H, the same size as the spindle, and perforated, as at H', centrally, preferably, for conducting the lubricant between the washers and the walls of the 90 seat and between the washers and the bottom of the spindle. By the provision of these independent rotatable washers it is evident that, should the lower spindle become overheated within its seat, the washer next to the spindle 95 may adhere thereto and rotate therewith, and the lubricant having run between each of the

washers, the spindle will rotate upon the next adjacent washer; and should it happen that this washer in time, from long running, becomes overheated, the spindle and adherent washers 5 will revolve upon the next adjacent washer, and so on down throughout the entire series, which may consist of as many washers as desired.

By experience, and it is well known to those 10 familiar with mechanism, it has been found that brass running against brass or steel against steel is attended with more friction and wear than when the two different metals are employed in connection with each other. For 15 this reason I form the washers alternately of brass and steel, so that, no matter which of the washers revolve and which stick, the steel spindle is always revolving upon a brass seat.

Having described my invention and its operation, what I claim is—

1. The combination, with a spindle, of a hollow step-case, a hollow spindle-step, and a series of perforated rotatable disks arranged in the said step, and an oil-duct communicating 25 therewith, substantially as specified.

2. The combination, with a spindle, of a hollow spindle-step, a series of perforated rotatable disks made of different metals, and an oil-duct communicating therewith, substantially 30 as specified.

3. The combination, with a spindle and a hollow step for the same, of a lower spindle mounted in the end of the spindle, a series of perforated disks interposed between the lower

end of the lower spindle and spindle-seat, and 35 an oil-duct communicating therewith, substantially as specified.

4. The combination, with a spindle, of a hollow exteriorly-screw-threaded spindle-step mounted in a fixed step-case, a series of perforated rotatable disks or washers arranged 40 between the spindle and within the step, and an oil-duct communicating with the step, substantially as specified.

5. The combination, with a spindle, of a 45 step-case mounted in a fixed bushing in the machine and provided with an interposed lining or sleeve, a screw-threaded hollow spindle-step mounted in the step-case, projecting pins for adjusting said spindle-step, and a set-wheel mounted thereon for retaining the seat in an adjusted position, substantially as specified.

6. The combination, with the base A, having the bridge A³ and opening A², and the bushing 55 A⁴, of the step-case B and its lining or sleeve, the spindle F, having the recess F', the lower spindle, G, the washers H, perforated as at H', the spindle-step C, pipe D', the nut D, and the oil-duct E', having the cup E, substantially as 60 shown and described.

In testimony whereof I affix my signature in presence of two witnesses.

FREDERICK LEININGER.
